UNITED STATES PATENT OFFICE.

THOMAS B. JEFFERY, OF CHICAGO, ILLINOIS.

VELOCIPED-E-HANDLE-BAR FASTENING.

SPECIFICATION forming part of Letters Patent No. 516,739, dated March 20, 1894.

Application filed April 17, 1893. Serial No. 470,669. (No model.)

To all whom it may concern:

Be it known that I, THOMAS B. JEFFERY, a citizen of the United States, residing at Chicago, county of Cook, and State of Illinois, have invented certain new and useful Improvements in Velocipede-Handle-Bar Fastenings, which are fully set forth in the following specification, reference being had to the accompanying drawings, forming a part thereof.

10 This invention relates to the securing of the stem of a handle-bar in the steering head or stem of the steering fork, particularly with reference to the vertical adjustability of the handle-bar, and it consists in an improved 15 construction of the steering head or tube with respect to its adaptation to be clamped onto the handle-bar stem.

In the drawings,—Figure 1 is a partly sectional detail elevation of the upper end of the 20 steering head and the handle-bar stem therein, showing the construction which is more commonly employed and upon which my invention is an improvement. Fig. 2 is a similar view of the corresponding parts in my improved construction. Fig. 3 is a section at 25 the line 3—3 on Fig. 2. Fig. 4 is a perspective of the latch for locking the adjusting nut.

A is the fork stem which is tubular.

B is the steering head penetrated longitudinally by the fork stem.

C C' are the two members of the ball-case which affords the upper bearing of the stem in the steering head, similar bearing being assumed at the lower end which is broken 35 away.

D is the handle-bar, and D', its stem, which is inserted down into the upper end of the tubular fork stem A.

In the construction heretofore more commonly employed, shown in Fig. 1, the upper member X of the ball-case is provided with an interiorly threaded hub and screwed onto the stem A, the jam-nut X' following it on the same thread to secure it in position. The 40 stem extending considerably above the ball-case and its jam nut is slit at several points, as shown in Fig. 1, so that it is adapted to be contracted by a clamp F, applied about the slit end, whereby the handle-bar stem D' is 45 grasped firmly by the tube. The defect in this construction is that the seat of the clamp being at the end, the end is reduced to allow

the ball-case and jam-nut to be passed over it to reach their thread (or, if the thread is run out to the end, it is mutilated by the clamp 55 and being of no service as a thread and adding no strength, might as well be cut away), and the metal is thus rendered thinner at the portion which serves to grasp the handle-bar stem than anywhere else; and since the entire strain of steering is transmitted to the fork stem at this point, it should be the strongest rather than the weakest point.

My improvement consists in making the upper member C of the ball-case slide freely on 60 the fork stem, locating the clamp F immediately above it, slitting the stem at a a, &c., at the portion encircled by the clamp, the slits preferably not extending to the end, and in providing the adjusting nut E² to operate upon the threaded terminal portion of 70 the stem above the clamp and preferably beyond the slits. If the slits extend into the threaded portion, or even into the end, the structure is not seriously weakened, because 75 the stem is not reduced where the clamp is applied below the threaded part; and the contraction of the tube, to permit which the slits are made, will not extend appreciably beyond the lower limit of the threaded portion, and 80 so will not diminish the diameter at the part where the nut is seated in the thread.

It will be understood that in order to adjust the bearing, it will be desirable to relax the grasp of the clamp, because the clamp becomes the medium through which the nut operates to crowd the bearing down on the stem, but a very slight relaxation serves to accomplish this purpose. The adjusting nut E² may be in effect a jam-nut setting against the 90 upper end of the clamp; for after the proper adjustment has been effected the clamp may be set so tightly that the adjusting nut may be jammed down against it without affecting the bearing. I prefer, however, to notch the 95 periphery of the adjusting nut, and lock it by a latch G, conveniently made in the form shown in Fig. 4, having its eye G', adapting it to be passed onto the end of the screw F' of the clamp, and to be held in place securely 100 by the nut F¹⁰. By this construction no severe strain is brought upon the thread of the adjusting nut or the thread on the stem with which it engages, nor is the accuracy of adjust-

ment of the ball-bearing liable to be disturbed, as by the setting of the jam-nut after it is adjusted; but the clamp being relaxed, and the latch G disengaged, the adjusting nut E² being rotated until the bearing is properly adjusted, the latch will be thrown again into engagement and the nut F¹⁰ tightened, and the clamp thereby set firmly onto the stem, while at the same time the latch is secured firmly 10 in its engagement with the nut without any disturbance of the bearing.

The clamp encircling the tubular fork stem may be made to hold the handle-bar stem within the fork stem, even without slitting 15 the fork stem, and if this is done, the leading advantage of the construction herein shown is still preserved,—that by locating the adjusting nut or adjustable stop above the clamp, the bearing being below the clamp, it is rendered 20 unnecessary to reduce the tubular fork stem where the clamp encircles it, its full strength being retained at that critical point. It will be evident also that an otherwise adjustable stop may be substituted for the adjusting nut without departing from the essential 25 feature of the invention. I consider, however, that slitting the stem is the preferable method, and that a nut is the preferable form of adjustable stop, and I therefore claim 30 these forms specifically.

I claim—

1. In combination, substantially as set forth, the tubular fork stem and the handle-bar stem extending within the same; the steering head journaled outside the fork stem, said fork stem being longitudinally slit near the upper end, and a clamp encompassing such slit portion adapted to contract the same about the handle-bar stem, the upper bearing 35 of the head being below the clamp and the tubular stem being threaded at the end, and an adjusting nut on said threaded portion above the clamp: substantially as set forth.
- 40 2. In combination with a steering head, a tubular steering fork stem pivoted thereto; a handle-bar stem inserted within such tubular stem; the upper bearing movable on the steering fork stem; the clamp above such bearing, and the adjusting nut above the clamp; the tubular stem being slit where it is encircled by the clamp, the end of the stem being threaded for the nut: substantially as set forth.
- 45 3. In combination with a slitted tubular fork stem, the upper bearing of the head

thereon; two movable parts above said bearing,—the clamp to contract the slitted portion and the adjusting nut above the clamp; a latch joined to one of said two parts and 50 adapted to engage the other to lock the adjusting nut against rotation when the clamp is set fast on the stem: substantially as set forth.

4. In combination with the steering head, 55 a tubular steering fork pivoted thereto, a handle-bar stem inserted in such tubular stem; a clamp encircling the tubular fork stem at a portion of the length of the latter within which the handle-bar stem extends; the upper bearing of the steering head and steering fork stem located below the clamp, and an adjustable stop above the clamp: substantially as set forth.

5. In combination with the steering head, 75 a tubular fork stem pivoted therein; a handle-bar stem inserted within such tubular stem, the upper bearing of the head and fork stem movable on the fork stem; said fork stem being slit longitudinally, and a clamp 80 encircling it at the slit portion, and an adjustable stop on the stem above the clamp: substantially as and for the purpose set forth.

6. In combination with the steering head, the tubular fork stem pivoted therein, a handle-bar stem extending within the tubular fork stem; the clamp encircling the latter stem at a part of its length within which the handle-bar stem extends; the upper bearing of the steering head and steering fork located 90 below the clamp; an adjusting nut screwed onto the fork stem above the clamp, such nut having a notched flange; and a spur movable into and out of engagement with the notches of such flange, and adapted to be made rigid 95 with the fork stem and handle-bar stem: substantially as set forth.

7. In combination with the slitted tubular fork stem and the clamp adapted to contract it at the slitted portion, the adjustable bearing below the clamp; the adjusting nut above the clamp; the latch pivoted on the clamp screw of the clamp and adapted to engage the adjusting nut to lock it against rotation: substantially as set forth.

In testimony whereof I have hereunto set my hand, at Chicago, Illinois, this 15th day of April, 1893.

THOS. B. JEFFERY.
